P. J. BIRD.

LUNCH BOX.

APPLICATION FILED JULY 17, 1908.

925,447.

Patented June 22, 1909.

UNITED STATES PATENT OFFICE.

PETER J. BIRD, OF NEW YORK, N. Y., ASSIGNOR TO MARY A. BIRD, OF NEW YORK, N. Y.

LUNCH-BOX.

No. 925,447.

Specification of Letters Patent.

Patented June 22, 1909.

Application filed July 17, 1908. Serial No. 444,122.

To all whom it may concern:

Be it known that I, PETER J. BIRD, a citizen of the United States, and a resident of the city of New York, borough of the Bronx, 5 in the county and State of New York, have invented a new and Improved Lunch-Box, of which the following is a full, clear, and exact description.

This invention relates to certain improvements in lunch boxes, and more particularly to that type of portable lunch boxes in which separate food drawers or compartments and a separate liquid receptacle are provided, together with means for heating said liquid receptacle, and, if desired, certain of said food compartments.

The special object of my invention is to provide certain improvements in the lunch box disclosed in United States Patent Number 735,656, granted August 4, 1903, whereby I simplify the construction, lessen the cost of manufacture, and render the device more efficient. To accomplish these objects, I entirely remove the solid partition, and may, 25 if desired, remove one of the asbestos slides. In my improved construction, I provide a skeleton framework which not only serves to support the liquid receptacle, but also supports the food drawers, and I provide a 30 separate compartment thoroughly insulated from the heat, so that food which it is not desired to heat may remain in the box during the heating of the liquid.

Reference is to be had to the accompanying drawings, forming a part of this specification, in which similar characters of reference indicate corresponding parts in all the figures, and in which—

Figure 1 is a front view of my improved 40 lunch box, showing the cover in its open position; Fig. 2 is a transverse section taken on the line 2—2 of Fig. 1, and showing the cover in its closed position and the outer casing in place; and Fig. 3 is a transverse section on 45 the line 3—3 of Fig. 1.

In the specific form of lunch box illustrated in the accompanying drawings, I employ a box or casing, preferably of sheet metal and having a top plate 10, a bottom 50 plate 11, end plates 12 and 13, a back 14, and a hinged front 15, constituting a cover. In most receptacles this box is substantially the same as that shown in the patent above referred to, although I eliminate the damper 55 mechanism for controlling the openings 16 in

the end wall 12. I also do not provide any opening in the top wall 10, and may, if desired, provide openings 17 in the back wall to facilitate the draft.

Within the box, I provide a liquid receptacle 18, two food receivers 19 and 20 each in the form of a sliding drawer, and a slide 21 of asbestos or other non-conducting material. The liquid-receptacle 18 is supported upon a bracket or frame, which includes vertically- 60 disposed members 22 and horizontally-disposed members 23 extending from adjacent the upper ends of said first-mentioned members to the end wall 13. The space beneath the horizontal members 23 serves to receive a 70 lamp 24, which latter is secured to a removable slide or tray 25. The liquid receptacle rests closely adjacent the inner surface of the end wall 13 and extends upwardly to adjacent the top wall 10. Adjacent its upper 75 end, the receptacle is provided with an offset portion 26, extending outwardly from the side opposite to the end wall 13. The liquid receptacle may be provided with any suitable form of closure, as, for instance, a screw 80 cap 27. Adjacent the under surface of the offset, I provide a flange 28 extending lengthwise of the receptacle and serving the double purpose of a support for the food drawer 19 and a heat deflector. The food drawer 19 85 rests upon the flange 28 and upon a bracket 29 carried by the end wall 12, and the upper edge of the food compartment comes directly below the top 10 of the box. The food drawer is of such width that one side comes 90 closely adjacent the end wall 12, while the other side comes closely adjacent the offset portion 26, so that the food drawer and the liquid receptacle mutually hold each other 95 against lateral movement.

Below the food drawer 19 is mounted the second food drawer 20, which is supported upon a bracket 30 carried by the end wall 12, and a bracket 31 carried by the side of the liquid receptacle. The bracket 30 is substantially the same as the bracket 29, and may be formed by riveting an L-shaped piece to the end wall 12, or may be formed from the metal removed in the punching of the holes 16, the metal being bent inwardly and 100 upwardly rather than being entirely removed. The bracket 31 is provided with a horizontally-extending portion 32 terminating beneath the food drawer 20, and a vertically-disposed portion 33 adapted to engage with 110

the side of the food drawer. The drawer rests upon the bracket 30 and the horizontally-extending portion 32, and is held against lateral movement by the end wall 12 5 and the vertically-extending portion 33. The portion 33 serves not only to hold the food drawer against lateral movement, but it serves also to insure a free passage for the hot gases rising adjacent the side of the 10 liquid receptacle. The flame and gases of combustion from the lamp 24 pass into direct engagement with the under surface of the liquid receptacle and up one side thereof. A portion of the gases pass beneath the food 15 drawer 20, while the remainder pass upwardly between said drawer and the side of the liquid receptacle into engagement with the under side of the offset and the flange 28, and thence beneath the food tray or 20 drawer 19 out the upper openings 16.

Beneath the tray or drawer 20, I provide the slide 21, which serves as a partition to separate a chamber 34 from the remainder of the interior of the box and prevent said 25 chamber from being heated by the lamp. The partition is provided with a horizontally-extending portion 21^a serving as a shelf, and is provided also with a vertically-extending portion 35 serving as a partition and also 30 serving as a support for the horizontal portion. The vertical portion 35 is disposed adjacent the vertically-disposed bars 22 of the liquid receptacle support, and the horizontally-extending portion extends across 35 the box and is supported at its opposite end upon brackets 36 carried by the end wall 12. The slide is preferably formed of asbestos, and may, if desired, have a metal border or binding 21^b along its edge to stiffen the same 40 and hold it in permanent form. The space beneath the slide is thus effectively subdivided from the remainder of the interior of the box, and any food placed within said space will remain unaffected by the heat of 45 the lamp 24. The horizontally-disposed portion 21 is preferably inclined upwardly slightly from the upper end of the vertical portion 35, so that the heat will be more effectively deflected against the bottom of 50 the food drawer or tray 20.

In connection with the box, I preferably employ an outer casing 37, substantially as shown in the previous patent referred to, said outer casing having an open bottom and 55 slideable down over the box and held in position by a strap 38. The cover 15 of the box is held closed by the outer casing 37, but I preferably employ small metal clips 39 pivoted to the end walls of the box adjacent 60 their upper front corners, and movable into engagement with the upper corners of the cover 15, to insure the retention of the cover 15 in its closed position after the casing 37 is removed.

65 The general construction of the box and

casing other than the interior details of the former, involve no feature of my invention and may be varied at will without departing from the spirit thereof.

Having thus described my invention, I 70 claim as new and desire to secure by Letters Patent:

1. In combination, a box or casing, a liquid receptacle supported therein adjacent one end thereof and having an offset portion 75 along one side adjacent its upper end, a burner beneath said liquid receptacle, and a food receiver within said casing and in engagement with said offset portion to hold said liquid receptacle and food receiver each 80 against lateral displacement.

2. In combination, a box or casing, a liquid receptacle supported therein adjacent one end thereof and having an offset portion along one side adjacent its upper end, a 85 burner beneath said liquid receptacle, a food receiver within said casing and in engagement with said offset portion to hold said liquid receptacle and food receiver each 90 against lateral displacement, and a flange carried by said offset portion for vertically supporting said food receiver.

3. In combination, a box or casing, a liquid receptacle disposed therein and having an offset portion adjacent its upper end, a 95 food receiver disposed closely adjacent said offset portion, a second food receiver below the first-mentioned receiver and spaced from said liquid receptacle, and a burner beneath said liquid receptacle. 100

4. In combination, a box or casing, a liquid receptacle mounted therein, a food receiver within said casing and adjacent said liquid receptacle, a burner beneath said liquid receptacle, and a flange carried by said 105 liquid receptacle and serving to support one edge of said food receiver and also serving to deflect the gases of combustion beneath the latter.

5. In combination, a box or casing, a liquid receptacle mounted therein, a burner beneath said liquid receptacle, a food receiver adjacent the upper end of said liquid receptacle and closely adjacent thereto, a second food receiver beneath the first-mentioned food receiver, and a bracket carried by said liquid receptacle and serving to support the last-mentioned food receiver and space the latter from said liquid receptacle, to permit the passage of gas from said burner 115 to said first-mentioned food receiver. 120

6. In combination, a box or casing, a liquid receptacle mounted therein, a lamp mounted beneath the same, a removable food receiver disposed within said casing and adjacent said liquid receptacle, and a slide beneath said food receiver and having a vertically-disposed portion adjacent said lamp and a horizontally-disposed portion spaced from the bottom of said food receiver and 130

forming with the bottom of said box or casing and one side thereof, a chamber insulated from the heat of the lamp.

7. In combination, a box or casing having a bracket upon the inner surface of one end thereof, a partition of non-conducting material having a horizontally-disposed portion, one end of which is mounted upon said bracket and a vertically-disposed portion serving to support the opposite side of said horizontally-disposed portion, a lamp adjacent said vertically-disposed portion, a liquid receptacle mounted above said lamp, and a removable food receiver mounted above said horizontally-disposed portion of the partition.

8. In combination, a box or casing, a frame therein including vertically-disposed portions secured to the bottom of said box and horizontally-disposed portions connecting said vertically-disposed portions and the ends of said box, a removable liquid receptacle mounted upon said horizontally-disposed portions, a lamp beneath said liquid receptacle, a bracket carried by the side of

said liquid receptacle, and a removable food drawer supported upon said bracket.

9. In combination, a box or casing, a frame therein, including vertically-disposed portions secured to the bottom of said box and horizontally-disposed portions connecting said vertically-disposed portions and the ends of said box, a liquid receptacle mounted upon said horizontally-disposed portions, a lamp beneath said liquid receptacle, a bracket carried by the side of said liquid receptacle, and a removable food drawer supported upon said bracket and spaced therefrom to leave a passage for the gases of combustion from said lamp, and serving to hold said liquid receptacle against lateral displacement.

In testimony whereof I have signed my name to this specification in the presence of two subscribing witnesses.

PETER J. BIRD.
